INVENTOR.

UNITED STATES PATENT OFFICE.

STANLEY M. UDALE, OF DETROIT, MICHIGAN, ASSIGNOR TO GEORGE M. HOLLEY, OF DETROIT, MICHIGAN.

CARBURETOR.

Application filed January 12, 1923. Serial No. 612,214.

The object of this invention is to prevent the opening of the throttle in a carburetor when the demand of the engine to which the carburetor is attached is not sufficient to 5 require a wide open throttle.

The preferred form of construction is shown in Figures I and II.

Figure I shows a cross sectional elevation taken in the plane of the throttle valve.

10 Figure II shows the transverse sectional elevation in a plane at right angles to the plane of the throttle, but the levers are shown thereon in elevation.

Figure III shows the same construction in 15 which the novel feature of the invention has been emphasized by exaggeration, namely the eccentric mounting of the throttle E.

In the figures A is the air entrance, B is the restricted mixing chamber, C is the fuel 20 nozzle discharging therein, D is the low speed fuel passage delivering adjacent to and in advance of the throttle valve E. F is the mixture outlet preferably made in a conical form, G is the throttle rod, H is 25 the throttle control lever which is freely mounted on the throttle rod G. J is a bell crank lever pinned to the throttle rod G, K is a projecting pin on the throttle lever H which strikes the bell crank lever J and 30 thereby closes the throttle, L is a spring connecting the pin K with a corresponding pin on the bell crank lever J, whereby as the throttle is closed the tension on the spring L is increased. M is the float chamber, N 35 is the fuel outlet therefrom controlled by a regulable needle O, P is the fuel well associated with the low and high speed outlets C and D, Q is the air vent to the well P. R and S are idling ports located respectively 40 above and below the closed position of the edge of the throttle valve E, T is the ordinary choke valve or strangling shutter in the air entrance which may either be of the fixed or flexible type.

45 In Figure III all the letters refer to similarly designated parts in Figure II, but this figure is not intended to illustrate the preferred construction, which is shown in Figures I and II. It will be clear from an 50 inspection of Figure III that although the throttle shaft G is located symmetrically with the conical outlet F it does not divide the throttle E symmetrically.

Operation.—The operation of this carburetor corresponds to the normal operation

of plain tube carburetors so long as the pin K contacts with the bell crank lever J. That is to say as the throttle control lever H is opened the suction on the throttle E being unbalanced by reason of the fact that 60 the throttle plate E is unequally divided by the throttle rod G, hence the flow of air from the chamber B to the mixture outlet F tends to open the throttle E. It follows that any movement of the lever H causes 65 a corresponding movement of the throttle E, providing the depression in the mixture outlet F is sufficiently great to overcome the tension of the spring L.

The only time at which the operation of 70 this carburetor differs from that of an ordinary plain tube carburetor is when the throttle is suddenly thrown wide open. Ordinarily such an operation is immediately followed by a drop in the suction above the 75 throttle, a certain amount of fuel which exists as vapor by reason of the vacuum to be precipitated as liquid and what is more important any precipitated fuel is immediately swept into the engine by the flow of 80 air which causes first a somewhat rich mixture followed immediately by a lean mixture and the characteristic irregular running ensues.

By the provision of the spring L and bell 85 crank lever J the opening of the throttle H does not open the throttle directly and immediately, the spring L tending to keep the throttle valve E closed until there is sufficient suction in the manifold to open it. 90 The result is that there is not a premature demand on the nozzle C and the lower edge of the throttle valve E remains in the vicinity of the low speed outlets R and S, thereby improving the operation during the 95 transfer from the low speed fuel nozzle B to the high speed fuel nozzle C.

The advantages gained, therefore, are 100 partly due to the fact that the sudden breaking of the vacuum above the throttle and subsequent deposition of the fuel and the sweeping in of the fuel by the free flow of atmospheric air is avoided and partly because the transfer from the low and high speed nozzle is made more gradually.

105 What I claim is:

In a carburetor having an air inlet, a fuel inlet, and a conical mixture outlet; an idling bypass opening into said mixture outlet; an elliptical throttle valve in said mixture out- 110

let, mounted upon a shaft passing through the axis of said conical outlet, but dividing said elliptical valve into two substantially unequal segments; the smaller segment being adjacent the outlet of said bypass; a two-armed lever fixed on said throttle shaft; a second lever adapted to be manually operated loose upon said shaft; a pin upon said manually operated lever to engage one arm of said two-armed lever, to force 10 said throttle valve to its closed position, and a spring connecting the second arm of said two-armed lever to said manually operated lever so as to be placed under tension when the throttle valve is closed by said 15 manually operated lever.

In testimony whereof I affix my signature.
STANLEY M. UDALE.
